LINEAR SWEEP GENERATOR

David O. McCoy, Cedar Rapids, Iowa, assignor to
 Collins Radio Company, Cedar Rapids, Iowa, a
 corporation of Iowa

Application April 10, 1950, Serial No. 154,910

5 Claims. (Cl. 250—27)

1

This invention relates in general to apparatus for obtaining a linear sweep voltage.

In the field of electronics it often becomes necessary to develop a voltage or current which increases linearly from zero to a predetermined value and then quickly falls to zero until another saw-tooth pulse is desired. A cathode ray oscilloscope, for example, requires that a linear signal be applied to one pair of plates to obtain a trace illustrating the variation, with respect to time, of another signal which is applied to another pair of plates. Earlier circuits for obtaining a "linear" sweep consisted of apparatus for applying a voltage to a condenser and then discharging it. The discharge of a condenser results in an exponential variation of voltage. More accurate circuits were developed for straightening out the exponential characteristic of a discharging condenser. The present invention relates to an improved linear sweep generator.

An object of this invention is to provide a sweep generator which will give a linear output.

A further object of this invention is to provide a linear sweep generator which has a quick recovery time, making it possible for a fast repetitive rate of actuating signals.

A feature of this invention is found in the provision for an improved boot-strap sweep generator which receives charging current for a condenser from a cathode follower.

Further objects, features, and advantages of this invention will become apparent from the following description and claims when read in view of the drawings, in which:

Figure 1 is a drawing of the improved boot-strap generator of this invention;

Figure 2 is a modification of the improved sweep generator of this invention, and;

Figure 3 is a circuit diagram of a conventional boot-strap generator.

Figure 3 illustrates a conventional boot-strap linear sweep generator which comprises the pentode tube V₁, the cathode follower V₂ and the diode V₃. A condenser C₁ is a relatively small one and the condenser C₃ is a relatively large one, for example, 1000 and 10,000 micromicrofarad, respectively. Tube V₁ has a control grid 11 to which is supplied a negative gate when a linear sweep is desired. Before the gate is supplied to the grid 11, tube V₁ is in a conducting state and current flows through the diode V₃, the resistor R₁, and the tube V₁, thus charging the condenser C₃ to a potential approximately equal to E_B. The condenser C₁ is substantially discharged during this period because of the low voltage drop across V₁. If a negative pulse having a time duration equal to the length of the desired sweep is supplied to the grid 11, the tube V₁ will be driven to cutoff, and the current pre-

viously flowing through V₁ from E_B will flow to the condenser C₁ to charge it. If the upper end of the resistor R₁ remains fixed in voltage the current through it will decay exponentially and the sweep voltage developed across C₁ would approach E_B exponentially. In this circuit, however, the upper end of R₁ is carried upward in voltage by the cathode follower V₂ through the coupling condenser C₃ with essentially the same rate of change as that of the plate of the tube V₁. This maintains the voltage across R₁, and, therefore, the current through R₁ essentially constant. The charging current flowing into C₁ is also essentially constant and therefore the rate of change of voltage across C₁ is essentially constant. This results in an output across the condenser C₁ which is substantially linear.

The realization of a linear sweep, however, in the above described circuit is only approximate because the voltage across R₁ does not remain constant but reduces during the sweep for the following reasons:

1. The cathode follower V₂ does not have a gain of one.
2. The ratio of maximum to minimum voltage across R₂, the cathode resistor of V₂, requires a large variation in cathode current with the associated large variation in grid voltage requirement.
3. The tube V₂ must operate near cutoff in the non-linear portion of the curve.
4. The current flowing through R₁ during the sweep stroke must be supplied from the condenser C₃ because the diode V₃ is non-conducting during this interval of time.

The above factors result in some shrinkage of the voltage across R₁ causing a consequent non-linear sweep. In spite of this disadvantage, the circuit produces a sweep output that is far more linear and has a far wider voltage excursion than can be produced by any other previously known circuit.

The recovery of the circuit presents a problem. At the end of the sweep stroke the voltage applied to the grid of V₁ reduces to zero and this tube becomes conducting, thus resulting in a rapid discharge of the condenser C₁. C₁ may be a relatively small condenser and the quick discharge is desirable. C₃, on the other hand, is a relatively large capacitor being in the order of ten times the value of C₁, and it must be recharged by the forward resistance of the diode V₃ in series with the cathode resistor R₂. The diode V₃ has a very low forward resistance, but the cathode resistor R₂ is usually large to minimize the slide-back characteristic of the cathode follower. Thus the time required to charge condenser C₃ is relatively long, which means that the sweep cycle must be initiated again after a relatively long time. This is a disadvantage.

Figure 1 illustrates the basic circuit of applicant's invention. It is to be noted that the cathode follower V_2 has its grid 12 connected to the cathode 13 of V_3 . The cathode 14 of the cathode follower is operated with a high initial voltage and the grid 12 of the tube is connected to the cathode through the resistors R_3 and R_4 . The upper end of the resistance R_4 has been connected to the cathode 13 of V_3 . The condensers C_2 and C_1 are connected in series between the diode V_3 and ground. This circuit allows the grid 12 of the cathode follower V_2 to be controlled by the plate 17 of V_1 through the condenser C_2 rather than by direct coupling as in the circuit of Figure 3. The current supply for the resistance R_1 will now be supplied from the cathode follower, and thus a large current drain on C_2 is eliminated.

C_2 may have a relatively small value. During the recovery of the circuit the condenser C_1 is discharged by V_1 . Condenser C_2 is recharged by the forward resistance of the diode V_3 and the plate resistance of V_1 . Because of the relatively low value of the capacitance of C_2 , the recovery time of the circuit will be relatively short.

The higher quiescent voltage across the resistor R_2 of V_2 results in higher gain and improved linearity of the output.

A lead 19 is connected to the plate 17 of V_1 and furnishes the linear output.

Examples of possible values of components of the circuits are:

R_1	megohm	1
R_2	ohms	47,000
R_3	do	2200
R_4	megohm	1
R_5	ohms	200
C_1	micromicrofarads	1000
C_2	do	1000
C_3	do	10000

V_1 and V_4 may be tube type 6AK5, V_2 may be a 2C51, and V_3 may be a 6AL5.

A modification of this invention is illustrated in Figure 2 wherein the cathode resistor R_2 is replaced by a pentode tube V_4 . Since a pentode tube is essentially a constant current device, it is ideal for this application.

It is seen that this invention relates to a linear sweep device which has a rapid recovery time.

Although this invention has been described with respect to particular embodiments thereof, it is not to be so limited as changes and modifications may be made therein which are within the full intended scope, as defined by the appended

I claim:

1. A circuit for obtaining a linear sweep voltage, comprising a first tube having a control grid which receives negative gates for driving the tube to cutoff, a resistor connected to the plate of said first tube, a cathode-follower tube with its cathode connected to the opposite side of said resistor, a first capacitor connected between the plate and cathode of said first tube, a third tube of the diode type with its plate connected to a positive voltage source and its cathode connected to the control grid of the cathode follower tube, a second condenser connected between the cathode of said third tube and plate of said first tube, a second resistor connected to the grid of said cathode follower tube, a third resistor connected between the cathode of the cathode follower tube and the second resistor, a fourth resistor connected between ground and said second and

third resistors, and an output taken from the plate of said first tube.

2. A system according to claim 1 wherein the plate of said cathode follower tube is connected to a high voltage source.

3. Means for obtaining a linear sweep signal, comprising a first electronic valve normally in the conducting state and driven to cutoff in response to negative control pulses received on its control grid, a first condenser connected between the plate and cathode of said first electronic valve, a second condenser connected to the first condenser, a second electronic one-way valve connected with its plate to a positive voltage source and its cathode connected to the second condenser, a cathode follower with its grid connected to the cathode of the second electronic valve, biasing means for the grid of the cathode follower, a first resistor connected between the plate of the first electronic valve and the cathode of the cathode follower, and output means connected to the plate of the first electronic valve.

4. Means for producing a linear sweep voltage, comprising a first electronic valve, a first resistor, a second electronic valve of the cathode follower type, said first electronic valve, first resistor, and second electronic valve connected in series between ground and a high potential with the plate of the second electronic valve connected to the high voltage side, a third electronic valve, a first capacitive means, a second capacitive means, with the third electronic valve and first and second capacitive means connected in series between a high potential and ground, the cathode of said third electronic valve connected to the grid of said second electronic valve, and output means connected to the plate of said first electronic valve to furnish a linear sweep voltage in response to negative pulses fed to the control grid of said first electronic valve.

5. A circuit for obtaining a linear sweep voltage comprising, a first tube having a control grid which receives negative pulses for driving the tube to cutoff, a second electronic valve of the cathode follower type with its plate connected to a high voltage supply, a first resistor connected between the plate of said first electronic valve and the cathode of said second electronic valve, first capacitive means connected between the plate of the first electronic valve and ground, a third electronic valve with its plate connected to a high potential source and its cathode connected to the control grid of said second electronic valve, second capacitive means connected between the cathode of said third electronic valve and said first capacitive means, a fourth electronic valve of the constant current type with its plate connected to the cathode of the second electronic valve through a second resistance, and third resistive means connected between the grid of the second electronic valve and the plate of the fourth electronic valve, and output means connected to the plate of said first electronic valve.
